ROLLING MILL FEEDING APPARATUS

Howard H. Talbot, Pittsburgh, Pa., assignor to
United Engineering & Foundry Company,
Pittsburgh, Pa., a corporation of Pennsylvania

Application January 8, 1934, Serial No. 705,701

13 Claims.

(Cl. 80—43)

This invention relates to an improvement in rolling mill equipment and more particularly to apparatus for feeding relatively thin flexible stock into a mill and tensioning it while it is being worked by the mill.

In the operation of the more modern rolling mills, and especially mills of the backed-up type in which relatively small working rolls are employed, difficulty is frequently encountered in entering the material between the working rolls. This is due principally to the fact that the bite angle of the small working rolls is such that it does not provide sufficient grip to readily pull the stock into the rolls by mere engagement with it. Also, because of the nature of the bite angle, if the end of the stock is at all deformed or warped, it makes it difficult to enter it in the mill. In fact, such mills are incapable of picking up stock which is as thick as they are capable of efficiently and effectively working without the stock being positively forced into them. Because of this and because of the lack of suitable feeding apparatus for such mills in the past they have in the most part been operated very inefficiently.

With these difficulties and the desirability of tensioning the material while it is being rolled in mind, it is the primary object of this invention, generally stated, to provide an improved and novel form of mill feeding apparatus which is capable of positively feeding into the working rolls of a rolling mill of the type employing small working rolls material that is too thick to be entered into the roll pass formed thereby without the application of a positive pressure and which is also adapted to tension the material after it is engaged in the mill.

Another object is to provide an apparatus of this character which is adapted to maintain the stock in proper alignment as it is being rolled and also tensioning it without in any way marking or marring its surface.

A further object is to provide a combined sticker and drag which is capable of also straightening the material and at the same time operating to feed new pieces of stock into the mill at a very rapid speed.

A still further object is to provide an apparatus embodying the aforementioned advantages which is simple and sturdy of construction, dependable in operation and capable of being readily applied to a mill in operation as well as one under construction.

These and various other objects, as well as the various other novel features and advantages of the invention, will be apparent when the following detailed description is read in conjunction with the accompanying drawings of which Fig. 1 is a sectional view taken on the line I—I of Fig. 3 of a feeding apparatus constructed in ac-

cordance with the invention; Fig. 2 a front elevational view of the same apparatus; Fig. 3 a plan view and Fig. 4 a horizontal section taken on the line IV—IV of Fig. 1 showing the feeding and leveling apparatus removed.

Referring in detail to the drawings, the numerals 201 and 202 designate the working and backing rolls respectively of a rolling mill of the backed-up type, which is the type of mill more particularly contemplated by this invention, although it is not necessarily so limited in its use. These rolls, as shown, are supported in the customary manner in a pair of roll housings 203, between which the feeding apparatus designated generally by the numeral 204 is in the most part located.

In the single embodiment of the invention illustrated, this feeding apparatus comprises a main stock and roll-supporting frame 205 which is of an oblong shape and mounted to ride on a pair of bars or rails 206 attached to the inner faces of the roll housings 203. For receiving these rails this frame is provided with a pair of oppositely disposed grooves 207 in its side walls which adapt it to be reciprocated back and forth in and opposed to the direction of travel of the stock into the mill for feeding purposes.

In the upper central portion of such frame there is mounted in suitable bearings 208 a plurality of spaced transversely extending rolls 209. Opposite these there are secured front and rear stock-supporting aprons or tables 211 and 212 which are preferably made of some suitable soft material, such as brass or wood, and projected beyond the ends of the frame 205. The forward ends of these aprons, as will be described more in detail hereinafter, is employed more particularly to guide the forward ends of the stock into the roll pass formed by the working rolls 201 of the mill and the rearward one to guide the stock into the feeding apparatus or over the main stock-supporting frame 205.

Above this main stock-supporting frame 205 there is provided a clamping frame 213 which consists essentially of a pair of side walls 214 and a plurality of cross ribs 215 so fabricated as to form a rigid structure similar to the main frame 205. On the bottom of this latter frame directly above the rolls 209 located in the center of the lower frame there is provided a pair of similar rolls 216 which are mounted in suitable bearings 217 with their axes disposed midway between the axes of the rolls 209 so that they will form with the latter rolls a stock-engaging and leveling pass for resisting the movement of the stock through the feeder to thereby tension it after it is engaged in the mill and straighten it before it reaches the mill.

On the side walls 214 of such clamping frames there is secured a pair of vertically disposed guid-

ing plates 218 which are extended downwardly along the sides of the main frame 205 and arranged to slide in two pairs of guides 219 secured to the sides of the latter frame which prevent 5 any endwise movement of the upper frame when lowered and raised to engage and disengage the stock mounted on the lower frame.

For raising and lowering the upper frame 213 and also reciprocating the entire apparatus toward and from the mill a hydraulic motor 221 is provided, being mounted for convenience on a pedestal 222 located directly below the feeder. While not shown, any suitable source of power supply may be utilized for operating this motor 10 which consists essentially of a cylinder 223 and a plunger 224 and any suitable control for controlling its operation may be employed.

To the plunger 224 of this motor there is attached a connecting rod 225 which in turn is connected to a cross head 226 located at the mill end of the compression cylinder. From this cross head a pair of connecting rods 227 is extended on opposite sides of the engine through guides 228 to the forward end of the cylinder 223 and joined 25 together by a shaft 229 on which a bifurcated connecting link 231 is pivotally mounted. The arms 232 of this connecting link are pivotally connected to the free ends of a pair of cranks 233 which are keyed to a shaft mounted in spaced 30 bearings 235 located on an extension 240 of the engine pedestal 222. On the outer ends of this latter shaft 234 outside of the bearings 235 there is secured a second and longer pair of cranks 236 which are extended upwardly toward the main 35 stock-supporting frame 205.

Secured to the under side of the lower stock-supporting frame 205 in suitable bearings 237 and 238 located adjacent the opposite ends thereof is a pair of shafts 239 and 241. On the ends of 40 these there are keyed two pairs of levers 242 and 243 respectively. The latter of these, which are located at the rear end of the frame are somewhat L-shaped and longer than the former and connected by pairs of links 244 with the upper 45 ends of the cranks 236 secured to the outer ends of the shaft 234 mounted on the extension 240 of the pedestal 222 to which the plunger 224 of the engine 221 is operably connected as previously described.

50 In substantial alignment with the shafts 239 and 241 mounted on the under side of the main frame 205 oppositely disposed pairs of trunnions 245 and 246 are secured to the inner faces of the side walls 214 of the upper clamping frame 213 and to these there are secured two pairs of connecting or lifting rods 247 and 248 which are also connected to the free ends of the levers 242 and to the levers 243 near their free ends, while between such latter levers at points directly opposite the points where the lifting rods 247 and 248 are connected there is secured a pair of side links 249.

With this arrangement whenever the plunger 224 of the engine 221 is moved away from the mill it causes the cranks 236 and the levers 242 and 243 to be rotated in the same direction, and thereby lifts the clamping frame 213 away from the lower frame 205 and also moves both frames away from the mill. When so operated, the upper frame 213 is adapted to support the upper leveling rolls 216 clear of the lower rolls 209, as shown in Fig. 2, so that the stock can be readily fed into the sticker which is thus disposed to a position for receiving the stock prior to feeding. 70 On the reverse stroke of the engine the cranks 75

236 and the levers 242 and 243 are rotated toward the mill. During the first part of this movement the upper frame 213 is moved into operative engagement with the lower frame, that is with the upper rolls 216 projecting below the surfaces 5 of the lower rolls 209 and in a position to flex the material so as to resist its movement therethrough, and hence tension it and straighten it as well as hold it in alignment as it is pushed into and pulled through the mill.

As soon as the stock is properly gripped in the feeder the continued movement of the plunger 224 in the same direction causes the feeder to be moved forward toward the mill eventually reaching its foremost position indicated by the 10 dotted lines 251 in Fig. 1. To prevent the feeder passing beyond this latter position a pair of resiliently mounted stops 252 is secured in suitable brackets 253 to the two sides of the lower frame 205 adjacent the rear end thereof, being so arranged that they engage the sides of the mill housings 203 when the frame is moved sufficiently in the forward direction. To accomplish the same result when the feeder is moved away from the mill the rails or bars 206 on which the main roll and stock-supporting frame 205 slide are provided with lugs 254 on their outer ends which are disposed to engage the rear end of such frame.

30 A difficulty encountered in forcing flexible material of the nature contemplated by the invention into the working rolls of a backed-up mill or mill having a roll pass of the same character is that the material buckles when it is pushed against the rolls unless the force is applied to it very close to the mill and when such buckling develops it is practically impossible to enter into the mill if any appreciable force is required for such purpose. A further difficulty is to apply the force to the material sufficiently close to the 35 roll pass of the mill to prevent this buckling.

To overcome these difficulties and at the same time permit a roller leveler to be used as a feeder and tensioning drag, a clamping shoe 255 is provided on the forward end of the upper roll-supporting frame 213 to cooperate with the platform or apron 211 on the lower frame 205 in forming 40 means for gripping and clamping the material sufficiently close to the mill to prevent its buckling when forced toward the rolls. Another purpose 45 of such shoe is to straighten the end of the material and thereby accurately register it with the roll pass. As shown, the shoe, which, like the apron 211, is preferably made of brass or some other suitable soft material, is attached to a frame 256 which is equipped at its rear upper corners with a pair of lugs 257 in which vertical 50 slots 258 are provided. In these slots a pair of pins 259 secured to the side walls 214 of the upper frame 213 is engaged, the slots being provided to permit the shoe 255 to be moved relative to the frame 213 so that it may be released as soon as the material is engaged in the mill. As will be appreciated it is desirable to so release this shoe at such time so that the material can 55 be drawn without injury through the feeder or drag.

For operating the shoe 255 in the manner referred to its supporting frame 256 is connected at its two ends by toggle links 261 and 262 to the walls 214 of the clamping frame 213. These links are so designed that when they are in alignment, and the clamping frame is operated to its stock-engaging position by the motor 221, they firmly 60 clamp the shoe against the apron 211. To hold 65

them in alignment when the material is being clamped against the apron 211 by the shoe 255 and to break the toggle so as to release the shoe after the material is engaged in the mill, a pair of rods 263 is connected to their central joints 264 and extended to the rear of the upper frame 213 through the cross braces 215. At their rear ends these rods are equipped with coil springs 265 which are disposed to bear against the rear brace 215 and suitable stops 266 secured to them at a point spaced from such brace. These springs both hold the toggle links 261 and 262 in alignment under normal conditions and return them to such position whenever the toggle is broken 10 and the forces breaking them are released.

To provide for automatically releasing the shoe 255 as the sticker reaches the forward end of its feeding travel under the influence of the operating motor 221, a pair of triggers 267 is pivotally mounted on the rear upper corners of the side walls of the clamping frame and so arranged that their lower ends bear against the rear ends of the toggle operating rods 263. The upper ends of these triggers are in turn disposed to engage a pair of adjustable stops 268 mounted on the inner walls of the roll housings 203 of the mill as the sticker approaches the forward end of its feeding travel. As a result they cause the trigger to rotate above their pivots 269 forcing the toggle rods 263 forward relative to the clamping frame 213 and thereby break the toggles as shown by the dotted lines 271 in Fig. 1 and lift the shoe.

In the event the stock or material is picked up by the mill before the shoe 255 is released by the triggers 267 it will, by friction, cause the shoe 255 to be pulled forward over the stationary apron 211 thereby causing the toggle to be broken and in such way relieve the pressure on the shoe, thus preventing any damage to the material under such conditions.

In operation with the feeder in its released position a piece of material is fed through it until the forward end thereof is against or substantially against the mill rolls. The operating motor 221 is then actuated to effect the feeding operation which consists essentially of three movements: First, the clamping frame 213 is moved into clamping engagement with the main supporting frame 205, causing the shoe 255 to firmly engage the end of the material between it and the apron 211 and rolls 216 to move to a position with respect to the rolls 209 providing a strengthening and tensioning pass; second, as soon as the clamping frame is moved to its stock-engaging position the entire apparatus is moved toward the mill; and third, as the apparatus nears the end of its feeding stroke the triggers 267 engage the stops 268 breaking the toggles 261 and 262 and lifting the shoe 255 to its released position. Thereafter the passage of the stock through the mill is resisted by the effect thereon of the rolls 209 and 216 which in addition to tensioning the stock strengthens it and maintains it in alignment without in any way marking or marring its surface.

After a piece of stock has passed through the mill the motor 221 is reversed to return the apparatus to its original position. During this operation of the motor the clamping frame is first moved to its released or elevated position and then rearwardly. As the triggers 267 move away from the stop 268 the springs on the toggle operating rods 263 retrieve these rods and return the toggles to their aligned clamping position.

To provide for repairing the apparatus with a

minimum of difficulty gear racks 272 are secured to the lower side edges of the main supporting frame and meshed with a pair of pinions 273 which are employed to move the apparatus after its link connections are removed out beyond the face of the mill so that the repairs can be made with ease. As shown, these pinions are keyed to a shaft 274 carried in bearings 275 attached to the mill housings 203, the ends 276 of the shaft being made non-circular to receive a turning tool 10 for effecting its rotation.

Among the advantages of the invention is the provision of a feeding apparatus for forcibly feeding flexible material into a rolling mill and tensioning it after it is engaged in the mill, which is simple and sturdy of construction, efficient and easy to operate at any desired speed, and at the same time adapted to both maintain the end and the axis of the material in proper alignment, as well as tension it without marring or impairing its surface. In addition, as will be appreciated, it may be adapted for use with any shape of material which is contemplated by the appended claims, as well as the fact that it may be modified in various ways as will be understood 20 by those skilled in the art without departing from the spirit of the invention.

I claim:

1. A combined sticker and drag for forcibly feeding thin metallic strip into a rolling mill 30 and tensioning it after it is engaged in the mill, comprising a roller leveler mounted for movement toward and away from the mill in the plane of the working pass of the mill and adapted to tension the strip, means for positively moving said 35 leveler in both of said directions, means secured to the forward end of said leveler for gripping the material and sticking the forward end thereof in the mill as the leveler is moved toward the mill, and means for releasing said gripping 40 means when the material is engaged in the mill.

2. A combined sticker and drag for forcibly feeding material to be rolled into a rolling mill 45 and tensioning it after it is engaged in the mill, comprising a roller leveler consisting of a lower 45 and a vertically adjustable upper roll supporting frame mounted for conjoint movement toward and away from the mill in the plane of the working pass of the mill, a single power unit for adjusting said upper roll supporting frame and 50 positively moving both of said frames in both of said directions, means secured to the forward end of said leveler for gripping the material and sticking the forward end thereof in the mill as the leveler is moved toward the mill, and means 55 for releasing said gripping means when the material is engaged in the mill.

3. A combined sticker and drag for forcibly feeding thin metallic strip into a rolling mill and tensioning it after it is engaged in the mill, 60 comprising a roller leveler consisting of a main lower roll supporting frame equipped with leveler rolls and a vertically adjustable upper roll supporting frame equipped with cooperating leveler rolls which are mounted for conjoint movement toward and away from the mill in the plane of the working pass of the mill, means for adjusting said upper frame to engage and disengage a piece of stock placed on said lower frame, means for positively moving both of said frames in the 65 manner described, means secured to the forward end of said leveler in spaced relation to said leveler rolls for gripping the material and sticking the forward end thereof in the mill as the leveler is moved toward the mill, and means auto- 70

matically operable at a predetermined point in the movement of the carriage toward the mill for releasing said gripping means.

4. A combined sticker and drag for forcibly feeding thin metallic strip into a rolling mill and tensioning it after it is engaged in the mill, comprising a roller leveler consisting of a lower and an upper roll supporting frame each equipped with cooperating leveler rolls mounted for movement toward and away from the mill in the plane of the working pass of the mill, means for positively moving said leveler in both of said directions, cooperating means secured to the forward end of said leveler frames for gripping the material and sticking the forward end thereof in the mill as the leveler is moved toward the mill, and means disposed to engage the mill and automatically release said gripping means when the material is engaged in the mill.

5. A combined sticker and drag for forcibly feeding thin metallic strip into a rolling mill and tensioning it after it is engaged in the mill, comprising a lower roll supporting frame equipped with a plurality of leveler rolls mounted for movement toward and away from the mill in the plane of the working pass of the mill, an upper roll supporting frame equipped with cooperating leveler rolls and mounted for vertical movement with respect to said lower frame as well as for horizontal movement therewith, means for raising and lowering said upper frame and positively moving both of said frames toward and from the mill, cooperating means secured to the forward ends of said frames for gripping a piece of material disposed therebetween and sticking the forward end thereof in the mill as the two frames are moved toward the mill, and means disposed to engage the mill and automatically release said gripping means when the material is engaged in the mill.

6. A combined sticker and drag for forcibly feeding thin metallic strip into a rolling mill and tensioning it after it is engaged in the mill, comprising a lower roll and stock supporting frame equipped with one or more leveler rolls mounted for movement toward and away from the mill in the plane of the working pass of the mill, an upper roll supporting frame equipped with one or more cooperating leveler rolls mounted for movement with and relative to said lower frame, means for positively moving said upper frame relative to said lower frame and both of said frames toward and from the mill, means secured to the forward ends of said frames for gripping the front end of the material and sticking it into the mill ahead of the leveler when it is moved toward the mill, and means automatically operable at a predetermined point in the movement of the roller supporting frames toward the mill for releasing said gripping means.

7. A combined sticker and drag comprising a lower roll and stock supporting frame equipped on its upper surface with one or more leveler rolls and mounted for movement toward and away from the working pass of a rolling mill, an upper roll supporting frame equipped with one or more leveler rolls disposed to cooperate with the first-mentioned rolls in forming a roller leveler and mounted for movement toward and from said lower frame and also therewith toward and from a mill, a stock supporting and clamping apron

mounted on said lower frame in front of and in line with the rolls thereof, a clamping shoe adjustably supported on said upper frame opposite said apron, a toggle connection securing said shoe to said upper frame, means for breaking said toggle connection to release said shoe, means disposed to actuate said toggle breaking means after a predetermined forward movement of said upper frame, a motor disposed below said lower frame, and means connecting said motor to said two frames in such a way as to operate said upper frame into and out of operative relation with said lower frame and both said frames toward and from the mill with which they may be used.

8. A combined sticker and drag for forcibly feeding material to be rolled into a rolling mill and tensioning it after it is engaged in the mill, comprising a carriage equipped with cooperating rolls disposed and adapted to engage a piece of stock and resist the passage thereof through them, means for positively moving said carriage toward and from the mill, cooperating means secured to the forward end of said carriage for gripping and feeding the material into a mill, and means for releasing said gripping means.

9. A sticker for forcibly feeding flexible stock into a rolling mill comprising cooperating clamping elements disposed for movement into and out of clamping engagement with a piece of stock, means for forcibly moving said clamping elements toward and from a mill, and means associated therewith disposed to engage the mill and automatically release said clamping elements when the material fed thereby is engaged in the mill.

10. For use in combination with a rolling mill, means operable as a drag for applying a tension to a piece of strip being passed through the mill, releasable clamping means arranged in front of the tensioning means for gripping the end of the strip, and means for actuating said clamping means to positively force the end of the strip into the bite of the mill rolls.

11. For use in combination with a rolling mill, a strip straightening device arranged in front of the mill and provided with means for resisting the passage of a piece of strip therethrough, means disposed between said straightening device and the mill for gripping the end of the strip, and means for actuating said gripping means to positively force the end of the strip into the bite of the mill rolls.

12. For use in combination with a rolling mill, a roller leveler arranged in front of the mill to engage and resist the passage of the stock through the mill, means arranged between said leveler and the mill for gripping the end of the stock, and means for actuating said gripping means to positively force the end of the stock into the bite of the mill rolls.

13. For use in combination with a rolling mill, a roller leveler comprising opposed sets of working rolls for engaging a piece of strip and resisting its passage through the mill, means for moving one of said sets of rolls into and out of operative position, means disposed between said leveler and the mill for releasably clamping the end of the stock, and means for actuating said clamping means to positively force the end of the stock into the bite of the mill rolls.

HOWARD H. TALBOT.

CERTIFICATE OF CORRECTION.

Patent No. 2,092,480.

September 7, 1937.

HOWARD H. TALBOT.

It is hereby certified that error appears in the printed specification of the above numbered patent requiring correction as follows: Page 4, second column, line 18, claim 8, after the word "cooperating" insert sets of opposed horizontally disposed; line 19, same claim, for "disposed and adapted" read arranged; same line and claim, before "engage" insert so; line 20, same claim, for "and" read as to; and that the said Letters Patent should be read with these corrections therein that the same may conform to the record of the case in the Patent Office.

Signed and sealed this 26th day of October, A. D. 1937.
